ENGINE STARTING APPARATUS

Roland Chilton, Keyport, N. J., assignor, by mesne assignments, to Eclipse Machine Company, Elmira Heights, N. Y., a corporation of New York

Application January 30, 1929, Serial No. 336,315

9 Claims. (Cl. 123—179)

This invention relates to inertia engine starters, and more particularly to an inertia starter for aeroplane engines which is adapted to be operated by hand or power, or both.

5 It is an object of the present invention to provide an inertia starter which is small, light, powerful and efficient in operation.

Another object is to provide a novel inertia starter embodying a yielding connection for the 10 inertia element which is light and simple in construction, but which is durable and which maintains its adjustment over long periods of use.

Another object is the provision of a novel inertia starter embodying a yielding connection 15 which is readily adjustable without disassembly of the starter.

Another object of the invention is to provide a novel inertia starter in which provision is made for securing full and positive engagement of the 20 starting means with a member of the engine to be cranked.

Another object is to provide a novel inertia starter which is adapted to be operated by manual or power means, or both, and in which the 25 power driving means is automatically disconnected upon operation of the manual cranking means.

Another object is the provision of a novel starter which is readily adapted for manual operation 30 from a plurality of angularly related positions with respect thereto.

Another object is the provision of an engine starter in which the parts are easily assembled and disassembled and are rigidly supported and 35 reinforced to insure proper cooperation at all times.

Other objects and advantages will become apparent to those skilled in the art by reference to the following description, taken in connection 40 with the accompanying drawings, wherein:

Fig. 1 is a front elevation of the device;

Fig. 2 is a section taken approximately on the line 2—2 of Fig. 1;

Fig. 3 is a section taken approximately on the 45 line 3—3 of Fig. 2;

Fig. 4 is a sectional detail taken approximately on the line 4—4 of Fig. 1;

Fig. 5 is a sectional detail corresponding to a portion of Fig. 2 of the drawings, and showing a 50 modification of the clutch shifting mechanism; and

Fig. 6 is a sectional detail further illustrating a portion of the structure shown in Fig. 5.

Referring first to Figs. 1 and 2 of the drawings, a generally oval-shaped casing 10 is shown which comprises a central portion 11 and front and rear closure members 12 and 13, suitably fixed thereto as by means of cap screws 14 and 15, respectively. The front closure member 12 is 60 provided with an annular flange 16 which is

spaced forwardly from the main portion thereon and which is provided with a series of openings 17 adapted to accommodate fastening devices such as the cap screws 18 which are threaded into suitable openings in the casing 19 of the engine to be started. The openings 17 in the flange 16 are formed as bayonet slots as indicated in Fig. 1, in order that the cap screws 18 may be started in the engine casing flange before the starter casing is applied thereto. In applying the starter, the heads of the cap screws pass through the enlarged portions of the openings 17, the starter is then rotated slightly to bring the cap screws into the barrel portion of said openings and then the cap screws are tightened down to hold the 15 starter firmly in place.

A starting motor 20 of any suitable type is mounted on the ends of the casing 10 and is suitably fixed thereto as by means of cap screws 21. The armature shaft 22 of the motor extends 20 within the casing 10 and is provided with a suitable bearing 23 mounted on the inner face of the casing member 11 on a bracket 24 formed integral therewith or suitably attached thereto.

A sleeve 25 is splined on the end of the shaft 22 within the casing 10, and is provided at its upper end (Fig. 2) with ratchet teeth 26 which are adapted to operatively engage ratchet teeth 27 which are formed on the lower end of a pinion 28 mounted loosely on the armature shaft 22. A 30 spring 29 is mounted on the shaft 22 between the bearing 23 and sleeve 25 and is arranged to urge the ratchet teeth 26 into engagement with the teeth 27, the arrangement being such that when the motor 20 is energized, the pinion 28 will be 35 driven therefrom through the ratchet connections, but when the hand cranking means, to be described hereafter, is used, the pinion 28 is allowed to freely overrun the armature shaft 22.

A countershaft 30 is rotatably mounted in suitable aligned bearings 31 and 32 seated in the casing members 10 and 11, respectively, and a gear 33 is freely journaled on an intermediate portion thereof in such a position that crown teeth 34 are in meshing relation with the teeth 35 of pinion 45 member 28. An antifriction bearing member 36 is mounted in the casing member 12 by suitable means such as the stud 37 so as to bear on the back of gear 33 opposite the pinion 28 in order to insure proper meshing engagement therebetween at all times.

An annular clutch member 38 is loosely mounted on the countershaft 30 as by means of a hub member 39 formed integral therewith or suitably fixed thereto. The clutch member 38 is slotted 55 radially as indicated at 40, forming a series of segmental clutch elements which are adapted to bear at their periphery against a corresponding clutch surface 41 formed inside of the rim of gear 33. The clutch member 38 is slightly dished 60

in cross section, as indicated in Fig. 2, and its diameter is such that it has normally a snug working fit within the clutch surface 41 of the gear 33. A dished spring plate 42 is loosely mounted on the countershaft 30 with its periphery bearing against the hub of clutch member 38, and with its central portion resting against the bearing 32. A clutch adjusting sleeve 43 is threaded on the end of the countershaft 30 and bears against the bearing 32 and thus controls the pressure of the spring plate 42 against the hub of clutch member 38. The gear 33 is provided at its hub with an inturned flange 44 which is adapted to bear against a radial projection 45 on the countershaft 30 and prevent motion of the gear 33 to the left in Fig. 2.

Pressure of the spring plate 42 against the clutch member will consequently cause the clutch members to be flattened and thus expand the segmental clutch members into frictional engagement with the surface 41 of gear 33 by a powerful toggle action. A screw plug 46 is removably mounted in the casing member 13 in alignment with the adjusting sleeve 43 and has a reduced extension adapted to bear against the end of countershaft 30, whereby the plug acts as a thrust bearing for said shaft and when removed allows the adjustment of the sleeve 43 by means of a suitable spanner or other wrench.

The hub 39 of clutch member 38 is coupled to the countershaft 30 by means of interengaging inclined cam teeth 47 and 48. The inclined cam teeth impose end reactions proportional to the driving load which overcome the spring 42 to release the clutch at a preset load in spite of variations in the frictional characteristics of the clutch surfaces. Countershaft 30 is provided with pinion teeth 49 which mesh with a main drive gear 50 rigidly secured to a driving barrel 51. The latter is mounted rotatably in casing member 12 by suitable means such as the bearing 52 clamped to the barrel by the threaded ring 53 and to the casing member 12 by the ring 54, fixed to the casing member 12 by suitable means such as screws 55.

The barrel member 51 is provided at its rear end with bevel gear teeth 56 adapted to mesh with a bevel gear 57, formed integral with or suitably fixed to, a cranking shaft 58 journaled in a suitable bearing 59 and protruding from the side of casing member 11 where it is adapted for engagement by any suitable cranking connection. It will be noted by reference to Fig. 3 of the drawings, that the seat 60 for the bearing 59 is duplicated at 60a to allow the cranking shaft 58 to be assembled in a different angular relationship to the casing 10 to adapt the starter for different installations.

A bearing 61 is mounted with a forced fit within the bevel gear 56, and a pinion shaft 62 is mounted at one end within said bearing and is provided with teeth 63 which are adapted to mesh with spur teeth 64 on the periphery of gear member 33. Pinion shaft 62 is fixed within a hub 65 of a flywheel 66 which is rotatably mounted on a bearing 67 seated on a stud 68 extending inwardly from the closure member 13 in alignment with bearings 61. Flywheel 66 is connected to rotate with the pinion shaft 62 by any suitable means such as a tapered pin 69 passing therethrough, so that rotation of the gear 33 will spin the flywheel 66 at high speed.

A jaw clutch member 70 is splined within the driving barrel 51 as indicated at 71 for rotation 75 with said barrel member and longitudinal move-

ment relative thereto. Clutch member 70 is provided with inclined teeth 72 which are adapted to engage and drive a member of the engine to be started when the clutch member is projected outwardly from the starter to engage therewith. The mechanism for controlling such engagement of the clutch member 70 is illustrated in Figs. 1 and 4, and comprises a manually actuated link 73 which is connected to swing a lever arm 74 fixed in any suitable manner on a vertical shaft 75. The lower end of shaft 75 has suitably fixed thereto a shifting arm 76 which carries at its end a shoe 77 which is adapted to run in a groove 78 (see also Fig. 2) in a ring member which is formed integral with the jaw clutch member 70 or is suitably attached thereto as by being threaded thereon.

The lever arm 74 is pointed at its end as indicated at 80 and is adapted to cooperate with a pointed detent member 81 which is urged toward the lever by suitable means such as a spring 82, the arrangement being such that the detent 82 serves to move the lever 74 to the clutch engaging or disengaging position by a positive snap action.

Figs. 5 and 6 illustrate a modified form of the invention in which the clutch shifting arm 76a is provided with a pair of lugs 77a which are adapted to straddle a flange 78a on the clutch member 70a. A double radial and thrust bearing 52a is provided for the driving barrel 51a, the outer race 54a of which is suitably attached to the inner side of the closure member 12 by suitable means such as the cap screws 55a.

The vertical shaft 75 (Fig. 1) of the clutch shifting means is provided with a suitable bearing 83 where it passes through the closure member 12, and an opening 84 is provided in the closure member 12 and its flange 16 in order to allow room for the movement of the shifting lever 76. This bearing and opening are duplicated at 85 and 86, respectively, in order that the shifting mechanism may be located conveniently for the operator in either of the cranking positions illustrated.

In operation, and starting with the clutch member 70 in its normal, retracted position, energization of the motor 20 will cause rotation of its armature shaft 22 to be transmitted through the pinion 35, gear 33, and pinion 62 to the flywheel 66 to cause rotation thereof at high speed. Rotation is also transmitted through the clutch members 38 to the countershaft 30 and through the pinion 49, driving gear 50 and barrel 51 to clutch member 70. When the flywheel 66 has attained sufficient angular velocity and sufficient energy is stored therein, the link 73 is actuated by the operator to cause the clutch member 70 to be swung into engagement with the member of the engine to be started. The energy in flywheel 66 is then transmitted through pinion 62, gear 33, clutch 38, countershaft 30, pinion 49, gear 50, and barrel 51 to the clutch member 70 to crank the engine.

It will be understood that the clutch member 38 is pre-set by means of the adjusting sleeve 43 to transmit without slipping a load sufficient to break loose and rapidly accelerate the engine to a speed corresponding to that of the flywheel, while protecting the parts from excessive load at the instant of connection of the starter to the engine, and in case of accidental backfiring of the engine. When the engine starts and overruns the clutch member 70, the inclination of the teeth 72 will cause the clutch member to be

5 moved out of driving position, and the detent 81 cooperates with the lever 74 to snap the clutch member 70 back to its normal position. The starting switch for the motor 20 may preferably be arranged to open at the time that the clutch member 70 is moved into engagement with the engine in order that if the engine should fail to start for any reason the motor 20 would not be subjected to a stall torque, and possibly in-
10 jured thereby.

15 In case the device is to be operated manually, rotation of shaft 58 by suitable cranking means will cause the rotation of barrel member 51 and the consequent accelerating of the flywheel 66 through the gearings 50, 49, 33 and 62. During this operation the ratchet sleeve 35 allows the pinion 28 to overrun the armature shaft 22 in order to relieve the operator from the load which would otherwise be occasioned by the necessity 20 of rotating the motor 20 at the same time as the flywheel 66. When sufficient energy has been stored in the flywheel 66, the connection of the starter to the engine and the automatic disconnection thereof when the engine starts, takes 25 place in the same manner as above described when the starter is operated by the motor 20.

30 It is to be expressly understood that the illustrated embodiments are not exclusive, and various other embodiments of the invention will now present themselves to those skilled in the art, while changes may be made in the construction, arrangement and proportion of parts, and certain features used without other features, without departing from the spirit of the invention. 35 Reference is therefore to be had to the claims hereto appended for a definition of the limits of the invention.

What is claimed is:

1. In an engine starter, a rotary driving member, a member arranged substantially in alignment therewith adapted to engage and drive a member of an engine to be started, a countershaft arranged substantially parallel to said members, a stage of reduction gearing connecting the driving member to the countershaft including a gear journaled on the countershaft and connected thereto by a pre-set friction clutch, a second stage of reduction gearing connecting the countershaft to the engine engaging member and including a gear arranged concentric with the engine engaging member, and a manually operated member nested between the driving member and said last mentioned gear, and adapted to drive the driving member through both stages of gearing.
2. In an engine starter, in combination, a driving member, a member adapted to engage and drive a member of an engine to be started, a gear connected to spin the driving member and yieldably connected to rotate the engine engaging member from the driving member, a motor shaft, a pinion loosely journaled thereon and meshing with said gear, and an overrunning clutch connecting said shaft and pinion.
3. In an engine starter, in combination, a driving member, a member adapted to engage and drive a member of an engine to be started, a gear connected to spin the driving member and yieldably connected to rotate the engine engaging member from the driving member, a motor shaft, a pinion loosely journaled thereon and meshing with said gear, and a sleeve splined on the motor shaft and having a ratchet connection to said pinion.
4. In an engine starter, in combination, an en-

gine engaging member, a gear yieldably connected to rotate said engine engaging member, a motor shaft, a pinion loosely journaled thereon and meshing with said gear, and an over-running clutch connecting said shaft and pinion, and permitting rotation of said pinion through a complete revolution independently of said shaft.

5 5. In an engine starter, in combination, an engine engaging member, a gear yieldably connected to rotate the engine engaging member, a motor shaft, a pinion loosely journaled thereon and meshing with said gear, and a sleeve splined on the motor shaft and having a connection to said pinion such that said pinion is free to rotate through a complete revolution independently of 10 said shaft.

15 6. In an inertia engine starter, an inertia member, a member adapted to engage and drive a member of an engine to be started, a driving motor, a gear adapted to drive the inertia member, 20 a countershaft geared to the engine engaging member and forming a journal bearing for said gear, said gear having a rim formed internally as a cylindrical clutching surface, and a friction disk 25 member splined on said countershaft and having arcuate peripheral surfaces arranged to adjustably engage within said rim, and means including two distinct sets of teeth on said rim for drivably connecting said motor and inertia member.

30 7. In an inertia engine starter, an inertia member, a supporting plate having a boss extending into the hub of said inertia member to constitute a journal base therefor, a member adapted to engage and drive a member of an engine to be 35 started, a motor driven gear connected to spin the inertia element, a countershaft geared to the engine engaging member and forming a journal bearing for said gear, said gear having a rim formed internally as a cylindrical clutching surface, a dished clutch member splined on said countershaft and having segmental peripheral surfaces arranged to engage said rim, and adjustable means threaded into said supporting plate for flattening the clutch member to vary 40 its clutching engagement with said rim.

45 8. In an inertia engine starter, an inertia member, a supporting plate having a boss extending into the hub of said inertia member to constitute a journal base therefor, a member adapted to engage and drive a member of an engine to be started, a motor driven gear connected to spin the inertia member, a countershaft geared to the engine engaging member, said gear being journaled thereon and being provided with a rim formed internally as a cylindrical clutching surface, a dished clutch member splined on said countershaft and having elastic segments with 50 peripheral surfaces arranged to engage within said rim, and adjustable means threaded into said supporting plate for forcing the clutch member towards said gear to flatten the segments and thereby vary their clutching engagement within 55 said rim.

60 9. In an engine starter, in combination, an engine engaging member, a gear yieldably connected to rotate the engine engaging member, a motor shaft, a pinion loosely journaled thereon and meshing with said gear, and a member 70 mounted on the motor shaft and having a one-way connection to said pinion such that said pinion is free to rotate through a complete revolution independently of said shaft.
